UNITED STATES PATENT OFFICE

151,412

DESIGN FOR AN AERIAL TOY

Narcy B. Ruczynski, Detroit, Mich.

Application August 1, 1946, Serial No. 132,164

Term of patent 3½ years

(Cl. D34—15)

To all whom it may concern:

Be it known that I, Narcy B. Ruczynski, a citizen of the United States and a resident of Detroit, in the county of Wayne and State of Michigan, have invented a new, original, and ornamental Design for an Aerial Toy, of which the following is a specification, reference being had to the accompanying drawing, forming part thereof.

The figure is a perspective view of the aerial toy, showing my new design.

The opposite side of the device from that shown in the drawing is substantially the same as the side illustrated.

I claim:

The ornamental design for an aerial toy, as shown and described.

NARCY B. RUCZYNSKI.
